ABSTRACT

A circuit breaker including a bellows member having a sufficient fatigue life is obtained. The circuit breaker includes a fixed electrode, a movable electrode, a container, a movable shaft, a bellows member, and a resin layer. The bellows member is disposed so as to surround a periphery of the movable shaft. The resin layer is connected to the plurality of uneven portions of the bellows member. The resin layer includes a first part, a second part, and a third part. The first part is connected to a first recess and has a first thickness. The second part is connected to a second recess and has a second thickness. The third part is connected to at least one of a plurality of intermediate recesses and has a third thickness. The third thickness is thinner than the first thickness and the second thickness.

CIRCUIT BREAKER

**CROSS-REFERENCE TO RELATED
APPLICATION**

This application is based on PCT filing PCT/JP2021/016986, filed Apr. 28, 2021, the entire contents of which are incorporated herein by reference.

TECHNICAL FIELD

The present disclosure relates to a circuit breaker.

BACKGROUND ART

Conventionally, a circuit breaker including a fixed electrode and a movable electrode that are disposed inside a container and a movable shaft that drives the movable electrode is known (for example, see Japanese Utility Model Laying-Open No. 2-064132). In the conventional circuit breaker described above, a bellows member is installed so as to surround a periphery of the movable shaft. In the circuit breaker described above, a stretchable synthetic resin layer is formed on an inner peripheral surface of the bellows member such that an uneven portion of the bellows member is embedded. In the circuit breaker, when impact energy applied to the bellows member due to an opening and closing operation of the movable electrode is consumed by deformation of the synthetic resin layer, so that vibration of the bellows member is prevented.

CITATION LIST

Patent Literature

PTL 1: Japanese Utility Model Laying-Open No. 2-064132

SUMMARY OF INVENTION

Technical Problem

In the conventional circuit breaker described above, because the synthetic resin layer is formed such that the uneven portion of the bellows member is embedded, mass of the entire bellows member increases. For this reason, amplitude at an initial stage of transient vibration of the bellows member during the opening and closing operation of the movable electrode increases, and as a result, there is a risk that a fatigue life of the bellows member is shortened.

The present disclosure has been made to solve the above problems, and an object of the present disclosure is to provide a circuit breaker including a bellows member having a sufficient fatigue life.

Solution to Problem

A circuit breaker according to the present disclosure includes a fixed electrode, a movable electrode, a container, a movable shaft, a bellows member, and a resin layer. The movable electrode is movable between a first position in contact with the fixed electrode and a second position away from the fixed electrode. The container holds the fixed electrode and the movable electrode therein. The movable shaft extends from an outside to an inside of the container and is connected to the movable electrode. The movable shaft moves along an extending direction of the movable shaft to move the movable electrode between the first

2

position and the second position. The bellows member is disposed so as to surround a periphery of the movable shaft. The bellows member includes a plurality of uneven portions. The bellows member connects the movable shaft and the container. The resin layer is connected to the plurality of uneven portions of the bellows member. The container includes a first connection portion. A first end of the bellows member is connected to the first connection portion. The movable shaft includes a second connection portion. A second end located on a side opposite to the first end of the bellows member is connected to the second connection portion. The plurality of uneven portions include a first recess, a second recess, and a plurality of intermediate recesses. The first recess is closest to the first connection portion. The second recess is closest to the second connection portion. The plurality of intermediate recesses are disposed between the first recess and the second recess. The resin layer includes a first part, a second part, and a third part. The first part is connected to the first recess and has a first thickness. The second part is connected to the second recess and has a second thickness. The third part is connected to at least one of the plurality of intermediate recesses and has a third thickness. The third thickness is thinner than the first thickness and the second thickness.

Advantageous Effects of Invention

According to the above, the circuit breaker including the bellows member having the sufficient fatigue life is obtained.

BRIEF DESCRIPTION OF DRAWINGS

35 FIG. 1 is a schematic sectional view illustrating a circuit breaker according to a first embodiment.

FIG. 2 is a schematic partial sectional view illustrating a bellows member in the circuit breaker of FIG. 1.

FIG. 3 is a schematic partial sectional view illustrating the bellows member in the circuit breaker of FIG. 1.

FIG. 4 is a schematic partial sectional view illustrating the bellows member in the circuit breaker of FIG. 1.

FIG. 5 is a schematic sectional view illustrating a circuit breaker according to a second embodiment.

45 FIG. 6 is a schematic partial sectional view illustrating a bellows member in the circuit breaker of FIG. 5.

FIG. 7 is a schematic partial sectional view illustrating the bellows member in the circuit breaker of FIG. 5.

FIG. 8 is a schematic partial sectional view illustrating the bellows member in the circuit breaker of FIG. 5.

50 FIG. 9 is a schematic partial sectional view illustrating a bellows member in a circuit breaker according to a third embodiment.

FIG. 10 is a schematic partial sectional view illustrating 55 the bellows member in the circuit breaker of the third embodiment.

FIG. 11 is a schematic sectional view illustrating a circuit breaker according to a fourth embodiment.

FIG. 12 is a graph illustrating a relationship between a 60 thickness of a resin layer of the bellows member and a recess in an uneven portion in the circuit breaker of the fourth embodiment.

FIG. 13 is a schematic sectional view illustrating a bellows member in a circuit breaker according to a fifth embodiment.

FIG. 14 is a schematic sectional view illustrating a circuit breaker according to a sixth embodiment.

FIG. 15 is a schematic partial sectional view illustrating a bellows member in a circuit breaker according to a seventh embodiment.

FIG. 16 is a schematic partial sectional view illustrating a bellows member in a circuit breaker according to an eighth embodiment.

FIG. 17 is a schematic partial sectional view illustrating a bellows member in a circuit breaker according to a ninth embodiment.

FIG. 18 is a schematic diagram illustrating a method for manufacturing the bellows member in the circuit breaker of FIG. 17.

DESCRIPTION OF EMBODIMENTS

Hereinafter, embodiments of the present disclosure will be described. The same components are denoted by the same reference numerals, and a repetitive description will be omitted.

First Embodiment

<Configuration of Circuit Breaker>

FIG. 1 is a schematic sectional view illustrating a circuit breaker according to a first embodiment. FIGS. 2 to 4 are schematic partial sectional views illustrating the bellows member in the circuit breaker of FIG. 1.

As illustrated in FIGS. 1 to 4, the circuit breaker of the first embodiment mainly includes a fixed electrode 4, a fixed shaft 5, a movable electrode 6, a container 1, a movable shaft 7, a guide member 8, a bellows member 9, and a resin layer 11. Movable electrode 6 is movable between a first position in contact with fixed electrode 4 and a second position away from fixed electrode 4.

Container 1 holds fixed electrode 4 and movable electrode 6 therein. For example, the inside of container 1 is held in a vacuum. Container 1 includes an upper flange 2 located above and a lower flange 3 disposed at a position opposite to upper flange 2. Fixed shaft 5 is fixed to upper flange 2. Fixed shaft 5 penetrates upper flange 2, and one end of fixed shaft 5 is disposed inside container 1. Fixed shaft 5 is connected to upper flange 2 so as to maintain airtightness. Fixed electrode 4 is connected to one end of fixed shaft 5.

Movable shaft 7 extends from the outside to the inside of container 1 through lower flange 3 interposed therebetween. Specifically, a through-hole is made in lower flange 3. Guide member 8 is inserted into the through-hole. Guide member 8 is fixed to lower flange 3. Guide member 8 is a cylindrical body and has a hole. A flange portion projecting outward is formed on a lower portion of guide member 8. The flange portion is in contact with a surface of lower flange 3 of container 1. Movable shaft 7 is inserted into the hole of guide member 8. An outer peripheral surface of movable shaft 7 is in slidable contact with an inner peripheral surface of the hole of guide member 8. Movable shaft 7 is disposed so as to extend from the outside to the inside of container 1 through guide member 8 interposed therebetween. Movable shaft 7 is connected to a drive mechanism (not illustrated) outside container 1. A device having an arbitrary configuration can be used as the drive mechanism, but for example, a spring type or electromagnetic type drive device may be used.

Movable electrode 6 is connected to a point of movable shaft 7. Movable electrode 6 is disposed at a position opposite to fixed electrode 4. Movable electrode 6 is disposed so as to be switchable between a state in which movable electrode 6 is in contact with fixed electrode 4 and

a state in which movable electrode 6 is separated from fixed electrode 4. Movable shaft 7 moves along an extending direction of movable shaft 7 to move movable electrode 6 between the first position and the second position.

The first position of movable electrode 6 is the position of movable electrode 6 at which movable electrode 6 is in contact with fixed electrode 4. From a different point of view, the first position is the position of movable electrode 6 in a state in which movable electrode 6 moves closest to fixed electrode 4 (closed state). At this point, in the circuit breaker, fixed electrode 4 and movable electrode 6 are in a conductive state.

The second position of movable electrode 6 is a position of movable electrode 6 at which movable electrode 6 is separated from fixed electrode 4. From a different point of view, the second position is the position of the movable electrode 6 in a state in which movable electrode 6 is farthest from fixed electrode 4 (open state). At this point, in the circuit breaker, fixed electrode 4 and movable electrode 6 are electrically insulated from each other. Specifically, when the drive mechanism described above operates, movable shaft 7 moves in a direction away from fixed electrode 4 in an axial direction in a state in which movable shaft 7 is in contact with the inner peripheral surface of the hole of guide member 8. As a result, when movable electrode 6 is separated from fixed electrode 4, energization between fixed electrode 4 and movable electrode 6 is cut off. This operation is the opening operation of the circuit breaker. In this manner, movable electrode 6 moves from the first position to the second position by the opening operation of the circuit breaker.

Bellows member 9 is disposed so as to surround the periphery of movable shaft 7. Bellows member 9 includes a plurality of uneven portions. In the uneven portion of bellows member 9, a protrusion (crest portion) and a recess (valley portion) are alternately arranged. Bellows member 9 can expand and contract along the axial direction of movable shaft 7. When movable shaft 7 moves in the direction away from fixed electrode 4, the recess and the protrusion of the uneven portion approach each other, whereby bellows member 9 contracts. When movable shaft 7 moves in the direction approaching fixed electrode 4, the protrusion and the recess of the uneven portion are separated from each other, whereby bellows member 9 extends. The number of protrusions and the number of recesses in the uneven portion of bellows member 9 can be set to any number as long as they can follow expansion and contraction accompanying the movement of movable shaft 7. For example, the number of protrusions may be greater than or equal to six, and the number of recesses may be greater than or equal to five.

Bellows member 9 connects movable shaft 7 and container 1. Specifically, a first end 9a of bellows member 9 is connected to the inner peripheral surface of lower flange 3 of container 1. For example, bellows member 9 and container 1 are connected by welding or brazing. In container 1, a portion to which first end 9a of bellows member 9 is connected is a first connection portion 1a.

An end plate 10 is connected to movable shaft 7. End plate 10 is a flat plate-shaped member extending in the direction intersecting the extending direction of movable shaft 7. End plate 10 preferably extends in the direction orthogonal to the extending direction of movable shaft 7. The shape of end plate 10 can be any shape, and for example, is a disk shape. End plate 10 is located inside container 1. End plate 10 is disposed so as to surround the outer peripheral surface of movable shaft 7. A second end 9b of bellows member 9 is connected to end plate 10. Second end 9b is an end located

on the side opposite to first end 9a of bellows member 9. For example, end plate 10 and bellows member 9 are connected by welding or brazing. A portion of end plate 10 to which second end 9b of bellows member 9 is connected is a second connection portion 10a. Bellows member 9 airtightly connects the inner surface of lower flange 3 and end plate 10. As a result, the space outside bellows member 9 and inside container 1 is airtightly held.

The plurality of uneven portions in bellows member 9 include a first recess 91, a second recess 92, and a plurality of intermediate recesses 93. Each of first recess 91, second recess 92, and intermediate recess 93 is a valley portion recessed toward the side of movable shaft 7 in the uneven portion. A protrusion is disposed between first recess 91, second recess 92, and the plurality of intermediate recesses 93. From a different point of view, each of first recess 91, second recess 92, and intermediate recess 93 is a portion in which a diameter of bellows member 9 is relatively small.

Each of the plurality of protrusions in bellows member 9 is a portion where the diameter of bellows member 9 is relatively large. In bellows member 9, first recess 91 is closest to first connection portion 1a. Second recess 92 is closest to second connection portion 10a. The plurality of intermediate recesses 93 are disposed between first recess 91 and second recess 92.

Resin layer 11 is connected to the inner peripheral side of the uneven portion of bellows member 9. Resin layer 11 may be connected to the outer peripheral side of the uneven portion of bellows member 9. Resin layer 11 is connected to the entire inner peripheral surface of the uneven portion of bellows member 9. Resin layer 11 may be connected to the entire outer peripheral surface of the uneven portion of bellows member 9. Any resin can be adopted as resin layer 11 as long as it is a resin that is rich in stretchability and can convert vibration energy into thermal energy by viscoelastic deformation. In addition, resin layer 11 may contain a filler that converts the vibration energy into the thermal energy by friction, such as a filler used in a damping coating material.

The thickness of resin layer 11 is locally different as described later. The details will be described below.

Resin layer 11 includes a first part 111, a second part 112, and a third part 113. First part 111 is connected to first recess 91. First part 111 has a first thickness t1. Second part 112 is connected to second recess 92. Second part 112 has a second thickness t2. Third part 113 is connected to the plurality of intermediate recesses 93. Third part 113 has a third thickness t3. Third thickness t3 is thinner than first thickness t1 and second thickness t2.

From a different point of view, the thicknesses (first thickness t1 and second thickness t2) of first part 111 and second part 112 that are located at both ends in the extending direction of bellows member 9 in resin layer 11 and connected to first recess 91 or second recess 92 are larger than the thickness (third thickness t3) of third part 113 of resin layer 11 located at a central portion in the extending direction.

For example, a lower recess group including first recess 91 and three intermediate recesses 93 and an upper recess group including second recess 92 and three intermediate recesses 93 are considered with the central portion in the extending direction of bellows member 9 as a boundary. In the lower recess group, first thickness t1 of first part 111 connected to first recess 91 of a first valley from the side of first end 9a is greater than third thickness t3 of third part 113 connected to three intermediate recesses 93 of a second valley to a fourth valley from the side of first end 9a. In the upper recess group, second thickness t2 of second part 112

connected to second recess 92 of the first valley from the side of second end 9b is greater than third thickness t3 of third part 113 connected to three intermediate recesses 93 of the second valley to the fourth valley from the side of second end 9b.

As long as the above-described thickness relationship is satisfied, thickness t3 of third part 113 connected to each of the plurality of intermediate recesses 93 may be the same or different from each other. First thickness t1 and second thickness t2 may be different or the same. In the circuit breaker of FIG. 1, the number of intermediate recesses 93 is 6, but the number of intermediate recesses 93 may be greater than or equal to 7 or less than or equal to 5.

In the circuit breaker described above, resin layer 11 is connected to all intermediate recesses 93, but third part 113 may not be connected to any one of intermediate recesses 93. For example, resin layer 11 may include first part 111 and second part 112, and resin layer 11 may not be connected to intermediate recess 93. In this case, assuming that third part 113 having third thickness t3 of zero is connected to intermediate recess 93, it can be said that the thicknesses (first thickness t1 and second thickness t2) of first part 111 and second part 112 are greater than the third thickness of third part 113. Third part 113 may be connected to at least one of the plurality of intermediate recesses 93. Also in this case, the thicknesses (first thickness t1 and second thickness t2) of first part 111 and second part 112 may be greater than third thickness t3 of third part 113 connected to one of the plurality of intermediate recesses 93.

Advantageous Effect

The circuit breaker of the first embodiment includes fixed electrode 4, movable electrode 6, container 1, movable shaft 7, bellows member 9, and resin layer 11. Movable electrode 6 is movable between a first position in contact with fixed electrode 4 and a second position away from fixed electrode 4. Container 1 holds fixed electrode 4 and movable electrode 6 therein. Movable shaft 7 extends from the outside to the inside of container 1 and is connected to movable electrode 6. Movable shaft 7 moves along an extending direction of movable shaft 7 to move movable electrode 6 between the first position and the second position. Bellows member 9 is disposed so as to surround the periphery of movable shaft 7. Bellows member 9 includes a plurality of uneven portions. Bellows member 9 connects movable shaft 7 and container 1. Resin layer 11 is connected to the plurality of uneven portions of bellows member 9. Container 1 includes first connection portion 1a. First end 9a of bellows member 9 is connected to first connection portion 1a. Movable shaft 7 includes second connection portion 10a. Second end 9b located on the opposite side of first end 9a of bellows member 9 is connected to second connection portion 10a. The plurality of uneven portions include first recess 91, second recess 92, and the plurality of intermediate recesses 93. First recess 91 is closest to first connection portion 1a. Second recess 92 is closest to second connection portion 10a. The plurality of intermediate recesses 93 are disposed between first recess 91 and second recess 92. Resin layer 11 includes a first part 111, a second part 112, and a third part 113. First part 111 is connected to first recess 91 and has first thickness t1. Second part 112 is connected to second recess 92 and has second thickness t2. Third part 113 is connected to at least one of the plurality of intermediate recesses 93 and has third thickness t3. Third thickness t3 is thinner than first thickness t1 and second thickness t2.

In this way, an increase in the mass of the entire assembly (bellows portion) of bellows member 9 and resin layer 11 can be prevented as compared with the case where entire resin layer 11 has a uniform thickness. Here, when a natural frequency of bellows member 9 decreases, the amplitude of the transient vibration generated in bellows member 9 increases. As the mass of bellows member 9 increases, the natural frequency decreases. Thus, when the increase in the mass of the entire bellows portion as described above, the increase in the initial amplitude in the transient vibration of bellows member 9 can be prevented during the operation of the circuit breaker.

Furthermore, the thickness of resin layer 11 (first thickness t_1 and second thickness t_2) is made sufficiently thick in first recess 91 and second recess 92 that are the first recess from first end 9a that is the connection portion between bellows member 9 and container 1 or second end 9b that is the connection portion between bellows member 9 and movable shaft 7, whereby the transient vibration of bellows member 9 can be effectively attenuated.

At this point, the transient vibration generated in bellows member 9 is a compressional wave of displacement transmitted in the extending direction of bellows member 9. The distortion of bellows member 9 due to the compressional wave becomes maximum in the vicinity of first end 9a and second end 9b that are both ends of bellows member 9. Furthermore, due to the structure of bellows member 9, the amount of strain generated in the recess tends to be greater than the amount of strain generated in the protrusion. For this reason, the amount of strain generated in first recess 91 and second recess 92 that are the recess of the first valley from both ends of bellows member 9 tends to be the greatest.

Therefore, the deformation amount of first part 111 and second part 112 of resin layer 11 connected to first recess 91 and second recess 92 is the greatest. Because the thicknesses (first thickness t_1 and second thickness t_2) of first part 111 and second part 112 are made relatively thick, the vibration energy can be sufficiently converted into the thermal energy in first part 111 and second part 112. As a result, the transient vibration of bellows member 9 can be effectively attenuated as described above.

As described above, in the circuit breaker described above, when third thickness t_3 of third part 113 of resin layer 11 connected to intermediate recess 93 is thinned, the transient vibration at an early stage can be attenuated by the deformation of first part 111 and second part 112 of resin layer 11 connected to first recess 91 and second recess 92 that are the first valley from the end while the increase in the amplitude of the transient vibration of the bellows portion is prevented. Thus, a fatigue life of bellows member 9 can be extended.

In the circuit breaker, third part 113 may be connected to all of the plurality of intermediate recesses 93. In this case, resin layer 11 is disposed on entire bellows member 9, so that the transient vibration of bellows member 9 can be more effectively attenuated.

Second Embodiment

<Configuration of Circuit Breaker>

FIG. 5 is a schematic sectional view illustrating a circuit breaker according to a second embodiment. FIGS. 6 to 8 are schematic partial sectional views illustrating the bellows member in the circuit breaker of FIG. 5. The circuit breaker in FIGS. 5 to 8 basically has a configuration similar to that of the circuit breaker in FIGS. 1 to 4, but the configuration of resin layer 11 is different from that of the circuit breaker

in FIGS. 1 to 4. That is, in the circuit breaker of FIGS. 5 to 8, the thicknesses (a fourth thickness t_4 and a fifth thickness t_5) of resin layer 11 connected to a first intermediate recess 931 and a second intermediate recess 932, which are the second valley from the end of bellows member 9, are greater than the thicknesses of resin layer 11 connected to the plurality of recesses (a third intermediate recess 933) located at and after the third valley from the end of bellows member 9. The details will be described below.

In the circuit breaker of FIGS. 5 to 8, the plurality of intermediate recesses 93 include first intermediate recess 931, second intermediate recess 932, and a plurality of third intermediate recesses 933. First intermediate recess 931 is closest to first recess 91. That is, first intermediate recess 931 is the recess of the second valley from first end 9a of bellows member 9. Second intermediate recess 932 is closest to second recess 92. That is, second intermediate recess 932 is the recess of the second valley from second end 9b of bellows member 9.

The plurality of third intermediate recesses 933 are disposed between first intermediate recess 931 and second intermediate recess 932. The number of the plurality of third intermediate recesses 933 is 4 in FIG. 5. The number of the third intermediate recesses 933 may be greater than or equal to 5 and less than or equal to 3.

Third part 113 of resin layer 11 includes a first intermediate part 1131, a second intermediate part 1132, and a third intermediate part 1133. First intermediate part 1131 is connected to the inner peripheral side of first intermediate recess 931. First intermediate part 1131 has fourth thickness t_4 . Second intermediate part 1132 is connected to the inner peripheral side of second intermediate recess 932. Second intermediate part 1132 has fifth thickness t_5 . Third intermediate part 1133 is connected to the inner peripheral side of the plurality of third intermediate recesses 933. Each of the plurality of third intermediate parts 1133 has a sixth thickness t_6 . Fourth thickness t_4 and fifth thickness t_5 are greater than sixth thickness t_6 .

Fourth thickness t_4 and fifth thickness t_5 may be the same as or different from each other. For example, fourth thickness t_4 may be greater than fifth thickness t_5 . Alternatively, fifth thickness t_5 may be greater than fourth thickness t_4 . Sixth thicknesses t_6 of the plurality of third intermediate parts 1133 may be the same as or different from each other. The recess in which third intermediate part 1133 is not formed may exist in the plurality of third intermediate recesses 933.

Advantageous Effect

In the circuit breaker, the plurality of intermediate recesses 93 may include first intermediate recess 931, second intermediate recess 932, and the plurality of third intermediate recesses 933. First intermediate recess 931 may be closest to first recess 91. Second intermediate recess 932 may be closest to second recess 92. The plurality of third intermediate recesses 933 may be disposed between first intermediate recess 931 and second intermediate recess 932.

Third part 113 of resin layer 11 includes a first intermediate part 1131, a second intermediate part 1132, and a third intermediate part 1133. First intermediate part 1131 may be connected to first intermediate recess 931 and have fourth thickness t_4 . Second intermediate part 1132 may be connected to second intermediate recess 932 and have fifth thickness t_5 . Third intermediate part 1133 may be connected to at least one of the plurality of third intermediate recesses

933 and have sixth thickness t6. Fourth thickness t4 and fifth thickness t5 may be greater than sixth thickness t6.

At this point, in first intermediate recess 931 and second intermediate recess 932, there is a possibility that the amount of generated distortion becomes greater than or equal to that of first recess 91 and second recess 92 due to superimposition of reflected waves at first connection portion 1a and second connection portion 10a as fixed ends and input waves incident from the central portion side of bellows member 9. As described above, the thickness (fourth thickness t4 and fifth thickness t5) of resin layer 11 at the portion where the distortion amount may be large is made sufficiently thick, so that the transient vibration of bellows member 9 can be effectively attenuated. As a result, the fatigue life of bellows member 9 can be extended.

In the circuit breaker, third intermediate part 1133 may be connected to all of the plurality of third intermediate recesses 933. In this case, the transient vibration of bellows member 9 can be more effectively attenuated.

Third Embodiment

<Configuration of Circuit Breaker>

FIGS. 9 and 10 are schematic partial sectional views illustrating bellows member 9 in a circuit breaker according to a third embodiment. The circuit breaker in FIGS. 9 and 10 basically has a configuration similar to that of the circuit breaker in FIGS. 1 to 4, but the configuration of resin layer 11 is different from that of the circuit breaker in FIGS. 1 to 4. That is, in the circuit breaker of FIGS. 9 and 10, the thickness (second thickness t2) of resin layer 11 connected to second recess 92 that is the first valley from the end of bellows member 9 on the side of end plate 10 is smaller than the thickness (first thickness t1) of resin layer 11 connected to first recess 91 that is the first valley from the end of bellows member 9 on the side of lower flange 3.

Advantageous Effect

In the circuit breaker, second thickness t2 may be thinner than first thickness t1. At this point, in bellows member 9, the amount of strain generated on the side of second recess 92 is smaller than the amount of strain generated on the side of first recess 91. This is because of the following reasons. That is, during the opening operation of the circuit breaker, end plate 10 moves together with movable shaft 7. As a result, an instantaneous displacement load is input to second end 9b of bellows member 9. As a result, in bellows member 9, the compressional wave of the displacement propagates from the side of second end 9b toward the side of first end 9a. The compressional wave is reflected by first end 9a connected to lower flange 3 to change the traveling direction. The compressional wave reflected by first end 9a propagates from first end 9a toward second end 9b. Because the compressional wave passes through first end 9a when the compressional wave is reflected by second end 9b, the compressional wave (transient vibration) is attenuated to some extent by plastic deformation of bellows member 9, viscoelastic deformation of resin layer 11, and friction of the filler when resin layer 11 contains the filler. For this reason, in bellows member 9, the amount of strain on the side of second end 9b tends to be smaller than the amount of strain on the side of first end 9a.

Thus, when second thickness t2 that is the thickness of resin layer 11 in the second recess 92 is made thinner than first thickness t1 that is the thickness of resin layer 11 in first recess 91, a damping effect can be exhibited while the

increase in the mass of the entire assembly (bellows portion) of bellows member 9 and resin layer 11 is prevented. As a result, the fatigue life of bellows member 9 can be extended.

Fourth Embodiment

<Configuration of Circuit Breaker>

FIG. 11 is a schematic sectional view illustrating a circuit breaker according to a fourth embodiment. FIG. 12 is a graph illustrating a relationship between a thickness of resin layer 11 of bellows member 9 and the recess in the uneven portion in the circuit breaker of the fourth embodiment. The circuit breaker in FIGS. 11 and 12 basically has a configuration similar to that of the circuit breaker in FIGS. 1 to 4, but the configuration of resin layer 11 is different from that of the circuit breaker in FIGS. 1 to 4. That is, in the circuit breaker of FIGS. 11 and 12, the thickness of resin layer 11 gradually decreases from the end (first end 9a and second end 9b) of bellows member 9 toward the central portion in the extending direction of bellows member 9.

From a different point of view, in the circuit breaker of FIGS. 11 and 12, the plurality of intermediate recesses 93 includes a first intermediate recess group 93a and a second intermediate recess group 93b. First intermediate recess group 93a is located at the end on the side of first recess 91. First intermediate recess group 93a includes three intermediate recesses 93 arranged along the extending direction of movable shaft 7. Second intermediate recess group 93b is located at the end on the side of second recess 92. Second intermediate recess group 93b includes three intermediate recesses 93 arranged along the extending direction of movable shaft 7. In the circuit breaker of FIG. 11, the plurality of intermediate recesses 93 are configured only by first intermediate recess group 93a and second intermediate recess group 93b. However, the plurality of intermediate recesses 93 may include one or a plurality of recesses arranged between first intermediate recess group 93a and second intermediate recess group 93b.

Third part 113 of resin layer 11 includes a first recess-side part 113a and a second recess-side part 113b. First recess-side part 113a is connected to the inner peripheral side of first intermediate recess group 93a. Second recess-side part 113b is connected to the inner peripheral side of second intermediate recess group 93b. As illustrated in FIG. 12, the thickness of first recess-side part 113a gradually decreases as the distance from first recess 91 increases.

In FIG. 12, a vertical axis represents the thickness of resin layer 11 (the thickness of first part 111 and first recess-side part 113a), and a horizontal axis represents the number of recesses (the number of valleys) counted from first end 9a of bellows member 9. 1 on the horizontal axis represents first recess 91. 2 on the horizontal axis indicates intermediate recess 93 closest to first end 9a of first intermediate recess group 93a. 3 on the horizontal axis indicates second intermediate recess 93 from the side of first end 9a in first intermediate recess group 93a. 4 on the horizontal axis indicates third intermediate recess 93 in first intermediate recess group 93a. FIG. 12 illustrates a graph when a plurality of recesses are disposed between first intermediate recess group 93a and second intermediate recess group 93b. In the configuration of the circuit breaker in FIG. 12, the thickness of resin layer 11 gradually decreases in the portion connected to the sixth recess from the side of first end 9a. The thickness of the portion of resin layer 11 connected to the sixth and subsequent recesses from the side of first end 9a is substantially constant as illustrated in FIG. 12. Similarly to first recess-side part 113a, the thickness of second recess-

11

side part **113b** gradually decreases as second recess-side part **113b** goes away from second recess **92**.

Advantageous Effect

In the circuit breaker, the plurality of intermediate recesses **93** may include first intermediate recess group **93a** and second intermediate recess group **93b**. First intermediate recess group **93a** is located at the end on the side of first recess **91**. First intermediate recess group **93a** may include three intermediate recesses **93** arranged along the extending direction of movable shaft **7**. Second intermediate recess group **93b** is located at the end on the side of second recess **92**. Second intermediate recess group **93b** may include three intermediate recesses **93** arranged along the extending direction of movable shaft **7**. Third portion **113** of resin layer **11** may include first recess-side part **113a** and second recess-side part **113b**. First recess-side part **113a** may be connected to first intermediate recess group **93a**. Second recess-side part **113b** may be connected to second intermediate recess group **93b**. The thickness of first recess-side part **113a** may gradually decrease as the distance from first recess **91** increases. The thickness of second recess-side part **113b** may gradually decrease as second recess-side part **113b** goes away from second recess **92**.

In this case, the thickness of resin layer **11** gradually decreases from the side of first recess **91** or the side of second recess **92** toward the central portion of bellows member **9**, so that local concentration of strain in bellows member **9** can be prevented unlike the configuration in which the thickness of resin layer **11** discontinuously changes. Thus, the fatigue life of bellows member **9** can be extended.

Fifth Embodiment

<Configuration and Advantageous Effect of Circuit Breaker>

FIG. 13 is a schematic sectional view illustrating a bellows member in a circuit breaker according to a fifth embodiment. The circuit breaker in FIG. 13 basically has a configuration similar to that of the circuit breaker in FIGS. 1 to 4, but the configuration of resin layer **11** is different from that of the circuit breaker in FIGS. 1 to 4. That is, in the circuit breaker of FIG. 13, the thickness of resin layer **11** is uniform in the circumferential direction of bellows member **9**.

From a different point of view, in the circuit breaker of FIG. 13, first recess **91** (see FIG. 1), second recess **92** (see FIG. 1), and intermediate recess **93** (see FIG. 1) of bellows member **9** are formed in an annular shape so as to surround movable shaft **7** (see FIG. 1). First part **111** (see FIG. 2), second part **112** (see FIG. 3), and third part **113** (see FIG. 4) are formed so as to extend in the circumferential direction surrounding the periphery of movable shaft **7**. First thickness **t1**, second thickness **t2**, and third thickness **t3** are uniform in the circumferential direction.

Here, when the thickness of resin layer **11** is locally different in the circumferential direction of bellows member **9**, the rigidity of the entire bellows portion changes in the circumferential direction. In this case, when the circuit breaker is operated, buckling is likely to be generated at a portion having low rigidity in bellows member **9**. In particular, when pressure acts on bellows member **9** by evacuating the inside of container **1** as in the circuit breaker described above, the buckling is likely to be generated.

12

When the thicknesses (first thickness **t1**, second thickness **t2**, third thickness **t3**) of first part **111**, second part **112**, and third part **113** of resin layer **11** connected to bellows member **9** are uniform in the circumferential direction as described above, the generation of the buckling as described above can be prevented. At this point, the thickness being uniform in the circumferential direction means that the amount of change in the thickness in the circumferential direction is less than or equal to 10% with respect to the average value in the circumferential direction.

Sixth Embodiment

<Configuration and Advantageous Effect of Circuit Breaker>

FIG. 14 is a schematic sectional view illustrating a circuit breaker according to a sixth embodiment. FIG. 14 illustrates the state in which movable electrode **6** of the circuit breaker is disposed at the second position away from fixed electrode **4**. The circuit breaker in FIG. 14 basically has a configuration similar to that of the circuit breaker in FIGS. 1 to 4, but the configuration of resin layer **11** is different from that of the circuit breaker in FIGS. 1 to 4. That is, in the circuit breaker of FIG. 14, the range of the thickness of resin layer **11** is determined based on the thickness of bellows member **9** and a pitch **p** of the uneven portion. Specifically, first thickness **t1** (see FIG. 2) of first part **111** and second thickness **t2** (see FIG. 3) of second part **112** in resin layer **11** are greater than or equal to 0.5 times the thickness of the uneven portion of bellows member **9**. First thickness **t1** and second thickness **t2** are less than or equal to 0.25 times pitch **p** of the plurality of uneven portions in the state where movable electrode **6** is disposed at the second position as illustrated in FIG. 14.

In this case, because resin layer **11** has a sufficient thickness by defining the lower limits of first thickness **t1** and second thickness **t2** of resin layer **11**, the damping effect on bellows member **9** can be reliably obtained. In addition, when movable electrode **6** is disposed at the second position, bellows member **9** is in the most compressed state. However, when the upper limits of first thickness **t1** and second thickness **t2** of resin layer **11** are defined as described above, adjacent portions of resin layer **11** can be prevented from coming into contact with each other even when bellows member **9** is in the most compressed state. As a result, bellows member **9** can be prevented from being excessively distorted due to contact between adjacent portions of resin layer **11**. Thus, the fatigue life of bellows member **9** can be extended.

Seventh Embodiment

<Configuration and Advantageous Effect of Circuit Breaker>

FIG. 15 is a schematic partial sectional view illustrating a bellows member in a circuit breaker according to a seventh embodiment. FIG. 15 corresponds to FIGS. 2 to 4. FIG. 15 illustrates the state in which a minute crack **20** is generated in first part **111** of resin layer **11**. The circuit breaker in FIG. 15 basically has a configuration similar to that of the circuit breaker in FIGS. 1 to 4, but the configuration of resin layer **11** is different from that of the circuit breaker in FIGS. 1 to 4. That is, in the circuit breaker of FIG. 15, resin layer **11** is a self-repairing resin layer **11a** containing a self-repairing material. At this point, the self-repairing material means a material that is repaired by itself or is repaired by a simple treatment when breakage such as crack **20** is generated. In

13

FIG. 15, crack 20 is filled by a repair 21 due to the self-repairing material. For example, rubber (for example, bromobutyl rubber) into which ionic crosslinking exhibiting reversible binding is introduced can be used as the self-repairing material. A resin layer in which fine capsules containing a self-repairing material are dispersed may be used as self-repairing resin layer 11a. In this case, when crack 20 is generated in self-repairing resin layer 11a, the self-repairing material in the capsule exposed at crack 20 may react by air or an external stimulus such as stress at the time of generation of the crack to fill the crack.

In this case, when minute crack 20 is generated in resin layer 11, crack 20 is repaired by the self-repairing material. Accordingly, the growth of crack 20 in resin layer 11 is delayed, and the damping effect by resin layer 11 can be maintained for a long time. Thus, the fatigue life of bellows member 9 can be extended.

Eighth Embodiment

<Configuration and Advantageous Effect of Circuit Breaker>

FIG. 16 is a schematic partial sectional view illustrating a bellows member in a circuit breaker according to an eighth embodiment. FIG. 16 corresponds to FIG. 2. The circuit breaker in FIG. 16 basically has a configuration similar to that of the circuit breaker in FIGS. 1 to 4, but the configuration of resin layer 11 is different from that of the circuit breaker in FIGS. 1 to 4. That is, in the circuit breaker of FIG. 16, a light-emitting resin layer 11b containing a stress-induced illuminant is used as resin layer 11. At this point, the stress-induced illuminant means a material capable of emitting excitation energy as light by mechanical stimulation from the outside in the state of being excited by an electric field or the like. Examples of the mechanical stimulation include impact, compression, tension, or torsion. For example, strontium aluminate that is doped with europium and structurally controlled can be used as the stress-induced illuminant.

The stress-induced illuminant included in light-emitting resin layer 11b is excited by the electric field caused by current flowing through the circuit breaker in the closed state of the circuit breaker. During the opening operation of the circuit breaker, the impact caused by the movement of movable shaft 7 is applied to bellows member 9, so that bellows member 9 vibrates. The vibration energy of bellows member 9 is converted into the thermal energy in light-emitting resin layer 11b as resin layer 11. Furthermore, when the stress-induced illuminant emits light by the vibration of bellows member 9, the vibration energy is also converted into light energy.

As described above, the vibration energy generated during the opening operation of the circuit breaker can be converted into not only the thermal energy but also the light energy in light-emitting resin layer 11b as resin layer 11. Thus, the damping effect by resin layer 11 can be increased.

Ninth Embodiment

<Configuration of Circuit Breaker>

FIG. 17 is a schematic partial sectional view illustrating a bellows member in a circuit breaker according to a ninth embodiment. FIG. 17 corresponds to FIG. 2. FIG. 18 is a schematic diagram illustrating a method for manufacturing the bellows member in the circuit breaker in FIG. 17. The circuit breaker in FIGS. 17 and 18 basically has a configuration similar to that of the circuit breaker in FIGS. 1 to 4,

14

but the configuration of resin layer 11 is different from that of the circuit breaker in FIGS. 1 to 4. That is, in the circuit breaker of FIGS. 17 and 18, first part 111 of resin layer 11 is installed on the outer peripheral side of first recess 91 in bellows member 9. As can be seen from FIG. 18, first part 111 is an annular resin member 11c having annular elasticity. First part 111 is in contact with the outer peripheral side of first recess 91 in the elastically deformed state. Resin layer 11 is similarly disposed on the outer peripheral side of second recess 92 (see FIG. 3) (not illustrated) of bellows member 9. Resin layer 11 provided on the outer peripheral side of second recess 92 may also be an annular resin member having elasticity similarly to first part 111 in FIG. 17.

As a method for forming resin layer 11 in the circuit breaker of FIG. 17, the following method can be used. That is, as illustrated in FIG. 18, first, annular resin member 11c that should become first part 111 of resin layer 11 is prepared as a raw material 22a. Annular resin member 11c as raw material 22a has a diameter d in an unloaded state. Diameter d is smaller than an outer diameter d1 of first recess 91 of bellows member 9.

Subsequently, stress is applied to annular resin member 11c as raw material 22a so as to widen the inner diameter, 25 and an intermediate raw material 22b is obtained. At this point, annular resin member 11c is in the elastically deformed state. The inner diameter of intermediate raw material 22b is greater than the outer diameter of bellows member 9 as illustrated in FIG. 18. When the stress on annular resin member 11c as intermediate raw material 22b is released, the inner diameter of annular resin member 11c decreases.

Intermediate raw material 22b described above is disposed at the position surrounding first recess 91 of bellows member 9, and the stress applied to the intermediate raw material 22b is released. As a result, as illustrated in FIG. 18, annular resin member 11c is installed on the outer periphery of first recess 91 in the elastically deformed state. As described above, because diameter d of annular resin member 11c in the unloaded state is smaller than outer diameter d1 of first recess 91, annular resin member 11c as resin layer 11 installed on the outer periphery of first recess 91 is in the elastically deformed state (the state in which annular resin member 11c is pressed against first recess 91). Thus, resin layer 11 is reliably fixed to the outer periphery of first recess 91.

As described above, annular resin member 11c may be installed on the outer periphery of second recess 92 of bellows member 9 to form second part 112 (see FIG. 3). 50 Furthermore, an annular resin member thinner than annular resin member 11c illustrated in FIGS. 17 and 18 may be installed on the outer periphery of intermediate recess 93 to form third part 113 (see FIG. 4). In bellows member 9, resin layer 11 made of annular resin member 11c may be provided only in first recess 91 and second recess 92. Alternatively, resin layer 11 may be provided only in one of first recess 91 and second recess 92. Resin layer 11 made of an annular resin member may be provided in all of the plurality of intermediate recesses 93. Alternatively, resin layer 11 made 55 of the annular resin member may be provided only on the outer periphery of a part of the plurality of intermediate recesses 93.

Advantageous Effect

In the circuit breaker, at least one of first part 111 and second part 112 (see FIG. 3) may be in contact with first

15

recess 91 or second recess 92 in the elastically deformed state from the outer peripheral side of bellows member 9.

In this case, for example, first part 111 or second part 112 of resin layer 11 made of the annular resin member is deformed (the diameter is increased) to be easily installed in first recess 91 or second recess 92 of bellows member 9. As a result, bellows member 9 and the circuit breaker having the extended fatigue life at low cost can be obtained without introducing special equipment forming the above structure.

It should be considered that the disclosed embodiments are an example in all respects and not restrictive. As long as there is no contradiction, at least two of the disclosed embodiments may be combined. The basic scope of the present disclosure is defined by not the above description but the claims, and it is intended that all modifications within the meaning and scope of the claims are included in the present invention.

The invention claimed is:

1. A circuit breaker comprising:
a fixed electrode;
a movable electrode movable between a first position in contact with the fixed electrode and a second position away from the fixed electrode;
a container to hold the fixed electrode and the movable electrode inside; and
a movable shaft extending from an outside to an inside of the container and connected to the movable electrode, wherein the movable shaft moves the movable electrode between the first position and the second position by moving along an extending direction of the movable shaft;
2. The circuit breaker according to claim 1, wherein a bellows member that is disposed so as to surround a periphery of the movable shaft, includes a plurality of uneven portions, and connects the movable shaft and the container; and
a resin layer connected to the plurality of uneven portions of the bellows member, wherein the container includes a first connection portion to which a first end of the bellows member is connected, the movable shaft includes a second connection portion to which a second end located on a side opposite to the first end of the bellows member is connected, the plurality of uneven portions include:
a first recess closest to the first connection portion;

16

a second recess closest to the second connection portion; and

a plurality of intermediate recesses disposed between the first recess and the second recess,

the resin layer includes:

- a first part that is connected to the first recess and has a first thickness;
- a second part that is connected to the second recess and has a second thickness; and
- a third part that is connected to at least one of the plurality of intermediate recesses and has a third thickness, and

the third thickness is thinner than the first thickness and the second thickness,

the plurality of intermediate recesses include:

- a first intermediate recess closest to the first recess;
- a second intermediate recess closest to the second recess; and
- a plurality of third intermediate recesses disposed between the first intermediate recess and the second intermediate recess,

the third part of the resin layer includes:

- a first intermediate part that is connected to the first intermediate recess and has a fourth thickness;
- a second intermediate part that is connected to the second intermediate recess and has a fifth thickness; and
- a third intermediate part that is connected to at least one of the plurality of third intermediate recesses and has a sixth thickness, and

the fourth thickness and the fifth thickness are thicker than the sixth thickness.

2. The circuit breaker according to claim 1, wherein the third part is connected to all of the plurality of intermediate recesses.

3. The circuit breaker according to claim 1, wherein the second thickness is thinner than the first thickness.

4. The circuit breaker according to claim 1, wherein the plurality of intermediate recesses include:

a first intermediate recess group that is located at an end on a first recess side and includes three intermediate recesses arranged along the extending direction of the movable shaft; and

a second intermediate recess group that is located at an end on the second recess side and includes three intermediate recesses arranged along the extending direction of the movable shaft,

the third part of the resin layer includes:

a first recess-side part connected to the first intermediate recess group; and

a second recess-side part connected to the second intermediate recess group,

a thickness of the first recess-side part gradually decreases as the first recess-side part is away from the first recess, and

a thickness of the second recess-side part gradually decreases as the second recess-side part is away from the second recess.

5. The circuit breaker according to claim 1, wherein each of the first recess, the second recess, and the plurality of intermediate recesses is formed in an annular shape so as to surround a periphery of the movable shaft, each of the first part, the second part, and the third part is formed so as to extend in a circumferential direction surrounding the periphery of the movable shaft, and the first thickness, the second thickness, and the third thickness are uniform in the circumferential direction.

6. The circuit breaker according to claim 1, wherein the first thickness and the second thickness are greater than or equal to 0.5 times a thickness of the plurality of uneven portions of the bellows member and less than or equal to 0.25 times a pitch of the plurality of uneven portions while the movable electrode is disposed at the second position. 5

7. The circuit breaker according to claim 1, wherein the resin layer includes a self-repairing material.

8. The circuit breaker according to claim 1, wherein the resin layer includes a stress-induced illuminant. 10

9. The circuit breaker according to claim 1, wherein at least one of the first part and the second part is in contact with the first recess or the second recess in an elastically deformed state from an outer peripheral side of the bellows member. 15
